UNITED STATES PATENT OFFICE.

JAMES A. MURPHEY, OF GERMANTOWN, PENNSYLVANIA.

MEANS FOR WAY-BILLING.

1,196,749.

Specification of Letters Patent. Patented Aug. 29, 1916.

Application filed February 5, 1912. Serial No. 675,612.

To all whom it may concern:

Be it known that I, JAMES A. MURPHEY, of Germantown, in the State of Pennsylvania, have invented a certain new and useful Improvement in Means for Way-Billing, whereof the following is a specification, reference being had to the accompanying drawing.

My improvement is particularly applicable to systems of way-billing packages for shipment by express, to lessen the time and labor required by the present system. The effect of my improvement may be best understood with reference to the present system, for instance, it is the present practice of Adams Express Company to have a "caller" read from each package the name of the shipper and addressee to a "writer" who is supposed to enter the same in the way-bill, to designate the entry with a number, and inform the "caller" of that number; the "caller" being supposed to mark said number somewhere on the package, by pencil or paint. The way-bill is then forwarded to the express office local to the address on the package. For instance, there are, at present, twenty-five shipments made by Adams Express Company from Philadelphia to Bristol, Pennsylvania, per day and it is the present practice to send a single way-bill with each shipment, averaging forty articles. Moreover, under the present system the auditing department of said company finds it necessary to enter in its books abstracts of way-bills which are sometimes very voluminous. Upon receipt of a package at that office, the clerk must refer to the way-bill to ascertain what, if any, charge to make for expressage. Such reference requires the clerk to scan some if not all of the forty entries in the way-bill to select the information regarding each package. Such a system not only necessitates expenditure of much time and labor, but affords opportunities for numerous errors which may be due to failures of the "caller" and "writer" to hear each other, or, to the checking clerks failing to hear each other, or, to mismarking either the package or the way-bill. To avoid such errors it has been proposed to write a separate way-bill for each package and send it with the latter. However, such practice would involve an expenditure of much more time and labor than the present

system in that it would necessitate the preparation of forty times the present number of way-bills.

I propose to retain the present system of "calling", "writing", and inclusion of a plurality of items in each way-bill, but provide the "writer" with a printed form constituting a way-bill having a series of distinctively numbered spaces and appropriately headed blank columns for matter descriptive of respective shipments, and provide the "caller" with a series of separable adhesive labels, to be attached to the respective shipments, respectively distinctively numbered in correspondence with the numbers on said way-bill; each of said labels having spaces for a date and for entries indicating whether the charge for shipment has been advanced, is to be collected, or has been paid; said spaces being conveniently respectively designated "Advance" "Collect" "Paid".

Figure I shows a way bill having appropriately-headed columns and a series of distinctively numbered spaces for entries relating to respective shipments. Fig. II shows a convenient form of printed adhesive label; being one of a series of labels which are similar but are distinctively numbered in correspondence with the numbers on the way-bill. In said figure, the reference mark A indicates an adhesive coating upon the back of one of the labels, and it is to be understood that all of the labels are provided with such a coating.

In accordance with my invention each package carries the information, contained in the way-bill, essential to enable the agent at the place of delivery to make the proper charges and entries independently of the way-bill; thus saving the time and labor now required to refer to the way-bill for such information for each package. Moreover, in accordance with my system a single line entry in the books required by the auditing department of the express company is found sufficient to account for all of the packages shipped on a certain date to a certain place from a given place of shipment. For instance, a single line entry may be made, accounting for two thousand packages as follows:—Jan. 16, 1912, packages A—14 to A—2014 from Phila. to Bristol, Pa.

I do not desire to limit myself to the precise details of construction and arrangement

herein described as various modifications may be made therein without departing from the essential features of my invention as defined in the appended claims.

5 I claim:—

1. Means for way-billing express shipments, including a printed form constituting a way-bill having a series of distinctively numbered spaces and appropriately-headed

10 blank columns for matter descriptive of respective shipments, and a series of separable adhesive labels, to be attached to the respective shipments, respectively distinctively numbered in correspondence with the

15 numbers on said way-bill; each of said labels having spaces for a date and for entries indicating whether the charge for shipment has been advanced, is to be collected, or has been paid; said spaces being respectively

20 designated "Advance" "Collect" "Paid".

2. Means for way-billing express shipments, including a printed form constituting a way-bill having a series of distinctively numbered spaces and appropriately-

25 headed blank columns for matter descriptive of respective shipments, and a series of separable adhesive labels, to be attached to the respective shipments, respectively distinctively numbered in correspondence with the

30 numbers on said way-bill; each of said labels having spaces for a date and for entries indicating whether the charge for shipment has been advanced, is to be col-

lected, or has been paid.

35 3. Means for way-billing express shipments, including a printed form constituting a way-bill having a series of distinctively numbered spaces and appropriately-

40 headed blank columns for matter descriptive of respective shipments, and a series of

separable adhesive labels, to be attached to the respective shipments, respectively distinctively numbered in correspondence with the

45 numbers on said way-bill; each of said labels having appropriately designated spaces for entries relating to the charge for shipment.

4. Means for way-billing express shipments, including a series of distinctively numbered adhesive labels; each having appropriately designated spaces for a date and for entries relating to the charge for shipment.

5. Means for way-billing express shipments, including a series of distinctively numbered adhesive labels; respectively having appropriately designated spaces for matter relating to respective shipments.

6. Means for way-billing express shipments, including a series of distinctively successively numbered, primarily connected but separable adhesive labels; each having appropriately designated spaces for matter concerning the shipment to which it relates, and indicating the date of shipment, and

whether the charge for shipment has been advanced, is to be collected, or has been paid.

7. Means for way-billing express shipments, including a series of distinctively 70 successively numbered, primarily connected but separable adhesive labels; each having appropriately designated spaces for matter concerning the shipment to which it relates.

8. Means for way-billing express shipments, including a printed form constituting a way-bill having a series of distinctively numbered spaces and appropriately designated columns for matter descriptive of respective shipments, and a series of separable adhesive labels, to be attached to the respective shipments; respectively distinctively numbered in correspondence with the numbers on said way-bill; each of said labels having appropriately designated 80 spaces for entries concerning the shipment to which it relates.

9. Means for way-billing express shipments, including a printed form constituting a way-bill having a series of distinctively numbered spaces and appropriately designated columns for matter descriptive of respective shipments, and a series of separable adhesive labels, to be attached to the respective shipments, respectively distinctively numbered in correspondence with the numbers on said way-bill; each of said labels having appropriately designated spaces for entries concerning the shipment to which it relates, indicating the date of shipment, 90 and whether the charge for shipment has been advanced, is to be collected, or has been paid.

10. Means for way-billing express shipments, including a printed form constituting a way-bill having a series of distinctively numbered appropriately designated spaces and appropriately designated columns for matter descriptive of respective shipments; a series of primarily connected but 100 separable adhesive labels, arranged to be respectively attached to the respective shipments, said labels being respectively distinctively numbered in correspondence with the numbers on said way-bill; each of said labels having appropriately designated spaces for a date and for entries indicating whether the charge for shipment has been advanced, is to be collected, or has been paid; said way-bill and labels each having entries 110 therein, the entries in said labels corresponding with the entries in said way-bill, and the entries in said way-bill being respectively identified with the respective labels.

11. Means for way-billing an express 11 shipment, including a distinctively numbered adhesive label for attachment to the shipment, and having appropriately designated spaces for a date and for entries indicating whether the charge for shipment has 115

been advanced, is to be collected, or has been paid; the number on said label corresponding with the number of an entry in the office records of said shipment.

5 12. Means for way-billing an express shipment, including an adhesive label for attachment to said shipment, bearing a distinctive printed number corresponding with the number of an entry in the office records 10 of said shipment, and said label having appropriately designated spaces for entries concerning the shipment to which it is attached.

13. Means for way-billing an express 15 shipment, including a label attached to and carried by said shipment to its destination; said label bearing a distinctive number corresponding with the number of an entry in the office records of said shipment, and said 20 label having appropriately designated spaces for entries concerning the shipment to which it is attached.

14. Means for way-billing express shipments, including a printed form having a 25 single series of spaces and appropriately headed columns for matter descriptive of respective shipments; all of said spaces being distinctively successively numbered in a single series; and a series of separable adhesive labels, adapted to be attached to the 30 respective shipments, respectively distinctively consecutively numbered in correspondence with the numbers on said way-

bill; each of said labels having spaces for a date and for entries indicating whether the charge for shipment is to be collected or has been paid; whereby each shipment carries the information, on said label, contained in said way-bill, essential to enable the agent at the place of delivery to make the proper charges and entries independently of the way-bill; and said way-bill constitutes a record of the respective labels and shipments.

15. Means for way-billing express shipments, including a series of separable adhesive labels adapted to be attached to the respective shipments, each bearing a printed number individually distinguishing it from all other such labels, and each having spaces 50 for a date and for entries indicating whether the charge for shipment is to be collected or has been paid; whereby each shipment, provided with such a label, carries the information essential to enable the agent at the place 55 of delivery to make the proper charges and entries independently of any way-bill separate from the shipment.

In testimony whereof, I have hereunto signed my name at Philadelphia, Pennsylvania, this thirty-first day of January, 1912.

JAMES A. MURPHEY.
